APPARATUS FOR PREHEATING THE AIR
SUPPLY FOR A FURNACE

Oliver Smalley, Pittsburgh, Pa., and Herbert A. Reece, Cleveland Heights, Ohio, assignors to Meehanite Metal Corporation, a corporation of Tennessee

Application June 3, 1940, Serial No. 338,468

7 Claims. (Cl. 266—14)

Our invention relates to furnaces and more particularly to metallurgical furnaces such as cupolas and the like, and to the operation of the same.

The invention disclosed herein is directed to the pre-heating of air supplied to a metallurgical furnace for the promotion of combustion therein. In the following discussion and description the operation and structure of a cupola for the remelting of metal will be referred to but it is to be understood that our invention includes the structure and operation of other furnaces and similar devices wherein a blast of air or other gases is supplied through a plurality of tuyères or like openings to the interior of the furnace or similar device.

The present invention utilizes the heat generated within the cupola for pre-heating the air delivered through the cupola tuyères to the interior of the cupola. During operation of the cupola the coke or other similar fuel charged into the cupola burns and generates a large amount of heat within the shaft of the cupola. The hot gases resulting from the combustion of the coke penetrate the charge of coke and metal within the cupola and arise up and out through the top of the cupola. The heat energy borne by these hot gases is ordinarily lost to atmosphere at the top of the cupola except for the small amount of heat radiated through the body of the cupola along the circumferential sides thereof.

In pre-heating systems prior to the present invention there has been an attempt to utilize some of the heat generated within the cupola by providing wall sections, in the sides of the cupola, of a heat conducting material such as iron rather than having them heat insulated completely by the fire brick lining of the cupola. In such previous systems the air to be supplied to the tuyères was passed along adjacent to, and outside of, the wall sections having the high degree of heat conductivity. In some of these systems of this class, the heat conducting wall sections were made hollow to permit the hot gases to flow through the hollow wall and to thus pass the heat through a relatively thin shell of the wall to the air flowing through the air supply system on the outside of the cupola.

The prior systems, however, were subjected to limitations, defects and disadvantages which did not provide for an efficient and proper pre-heating of the air supply. The air passing through the conduits or wind box of the system was heated only upon one side, that is, only through the wall next adjacent to the cupola body. There was a

lack of uniformity in the heating of the total air blast delivered through the system and there was no assurance of a delivery of uniformly heated air to the plurality of tuyères. Moreover, the maximum amount of heat exchange between the hot gases and the air was greatly limited by the arrangement of the parts and the inherent disability of the structure. Other limitations preventing the production of the desired results in pre-heating air are apparent upon inspection of the structure of the previous systems and particularly in the light of the disclosure of the results obtained from the present invention.

It is an object of the present invention to obviate the limitations, defects and disadvantages of the prior systems.

Another object of the invention is the provision of an improved system of pre-heating the air supplied to a cupola affording results and presenting advantages not heretofore known or obtainable.

Another object is the provision for the obtaining of the maximum amount of heat from the hot gases of the cupola in pre-heating the air supplied to the cupola.

Another object is the provision for obtaining a more uniform heating of the air supplied to a cupola.

Another object is the provision for a distribution of air flow in a system to obtain a uniform heating of the air supplied to a plurality of cupola tuyères.

Another object is the provision of improved apparatus for the utilization of heat generated by a cupola for the efficient pre-heating of the air supplied to the tuyères of the cupola.

Another object is the provision for establishing a more efficient heat exchange relationship between the hot gases of the cupola and the air being supplied to the cupola.

A still further object is the provision of an air pre-heating system affording results not heretofore obtainable.

Other objects and a fuller understanding of our invention may be had by referring to the following description and claims, taken in conjunction with the accompanying drawing, in which:

Figure 1 is a cross-sectional view taken lengthwise of a cupola and wind box embodying our invention and is a view looking in the direction of the arrows 1—1 of Figure 2;

Figure 2 is a transverse cross-sectional view taken through the line 2—2 of Figure 1;

Figure 3 is a cross-sectional view taken length-

wise of a cupola and wind box embodying a modified form of our invention and is a view looking in the direction of the arrows 3—3 of Figure 4; and

Figure 4 is a transverse cross-sectional view taken through the line 4—4 of Figure 3.

Inasmuch as the invention disclosed herein is directed particularly to the wind box, the portion of the cupola adjacent thereto and the heating arrangement associated therewith, it has not been considered necessary to show all parts of the cupola nor all views thereof in the several figures. The portions of the cupola and wind box not shown, however, may be considered as having the usual and well known form. Also, for purposes of simplicity in illustration, the usual tap hole and slag hole are not shown. It has also been considered unnecessary to illustrate such other openings as a clean-out door, breast arch or drop-bottom door. The cupola to which the invention is associated and which is described herein may be considered, however, as having all of the parts necessary for the usual operation of the same.

As shown in the several views of the drawing, the cupola body or shell 21 is in the form of a cylindrical shaft, the inner walls of the cupola body 21 being lined by the fire brick lining 24. The body 21 and the lining 24 are mounted upon the usual bottom plate 27 and thereby forms the enclosed shaft or stack of the cupola. Suitable supports 26 form a base for the support of the cupola.

A wind box 22 of cylindrical shaft is mounted upon the cupola body 21 by welding or other suitable means and in the embodiment shown, the outer wall of the cupola body forms one of the enclosing walls of the wind box 22. It is therefore seen from the view of the drawing that the wind box 22 forms an enclosed jacket surrounding the cupola body 21 in such a way that air introduced into the wind box may circulate entirely around the cupola body.

An inlet conduit 23 is in communication with an air blower or other source of an air blast (not shown) and the inlet conduit 23 is connected to the upper portion of the wind box 22 so as to afford communication between the air blower and the inlet opening 25 of the wind box 22.

In the cupola illustrated there are six tuyères 30, 31, 32, 33, 34 and 35 are shown in dotted lines in transverse cross-sectional views of the drawing and three of the tuyères 30, 31 and 32 as seen from the inside of the shaft of the cupola are illustrated in the cross-sectional views taken lengthwise of the cupola. These six tuyères are of substantially equal size and are uniformly spaced around the periphery of the cupola. The tuyères enter the cupola body at a low level in the cupola and communicate with the lower portion of the wind box.

The description of the first form of the invention is made in conjunction with the showing of Figures 1 and 2. In conjunction with said figures there is shown an upper partition 37 and a lower partition 38 spaced apart and dividing the wind box into an upper compartment adjacent the inlet 25, a lower compartment adjacent the six tuyères and an intermediate compartment forming the heating chamber 42. A plurality of tubular conduits 39 extend from the partition 37 to

the partition 38 to provide communication between the upper portion and the lower portion of the wind box, the conduits 39 being adapted to accommodate a flow of air down through the wind box from the inlet 25 to the tuyères. The conduits 39 are arranged in regular intervals around the wind box and are of equal size to substantially equalize the flow of air therethrough from the wind box inlet to the plurality of tuyères. The arrangement of the partitions and conduits is such that air is sealed from the heating chamber 42 but as it flows through the tubes 39 is immediately adjacent to the heating chamber.

15 A plurality of lower holes 40 extend through the wall of the cupola and provide communication between the interior of the cupola and the heating chamber 42. A plurality of upper holes 41 also extend through the wall of the cupola 20 to provide communication between the interior of the cupola and the heating chamber 42. Hot gases bearing heat generated by the combustion within the cupola may flow outwardly through the holes 40 into the heating chamber 42 and then upwardly and back into the stack of the cupola again through the upper holes 41. The holes 40, the heating chamber 42 and the upper holes 41 thereby form a by-pass by which the hot gases of the cupola are taken out of the side of the walls of the cupola, heat removed from the hot gases in the heating chamber, and the gases thereupon reintroduced back into the stack of the cupola from whence they are carried up out into atmosphere from the top of the cupola.

25 Inasmuch as the tubular conduits 39 are spaced apart and are also spaced away from the outer walls of the wind box and the wall of the cupola the hot gases in the heating chamber may freely circulate around within the chamber and entirely surround the conduits 39 through which the air is passing. The tubular conduits 39 have a relatively large expanse of heat exchange surface and all of this large expanse of heat exchange surface is utilized in the heating of the air within the conduits by the hot gases surrounding the conduits.

30 As the heat is equally distributed to all of the conduits and all of the conduits accommodate an equal supply of air there is a uniform heating of all portions of the air blast delivered to the lower portions of the wind box and then into the tuyères. The greatest degree of heat exchange is obtained by the arrangement of the plurality of conduits containing the air flow and surrounded by the hot gases. The arrangement conserves the heat for a maximum utilization thereof in pre-heating the air supplied to the tuyères by the air supply system.

35 A modified form of the invention is illustrated in Figures 3 and 4. In this arrangement the upper portion of the wind box and the lower portion of the wind box are separated by a plurality of tubular conduits 44, the partitions 37 and 38 in effect dividing the wind box into two separate compartments. There is a reversal of position 40 between the air and the hot gases in the modified arrangement of Figures 3 and 4. A plurality of pipes or conduits 45 are disposed within and extend longitudinally of the tubes 44, the pipes 45 being of smaller diameter than the tubes 44. The pipes 45 have connecting portions extending inwardly to communicate with the interior of the cupola through the walls thereof, the lower holes 46 providing communication with the lower 45 end of the pipes 45 and the upper holes 47 pro-

viding communication with the upper end of the pipes 45. Hot gases are therefore by-passed out through the holes 48 upwardly through the pipes 45 and back into the shaft of the cupola through the holes 47.

The pipes 45 are concentrically disposed within the tubular conduits 44 and the side walls of the pipes 45 are spaced from the side walls of the tubular conduits 44. Therefore, air passing downwardly through the conduits 44 entirely surrounds the pipes 45 through which the hot gases flow. A maximum amount of heat exchange surface is afforded by the tubular pipe 45 and this maximum amount of surface is fully utilized by the arrangement shown for an efficient heat exchange between the hot gases and the air to be heated. The pipe conduits are of uniform size and are uniformly arranged around the outside of the body of the cupola. The air flowing from the upper portion of the wind box down through the conduits 44 is uniformly heated to be supplied to the plurality of tuyères from the lower portion of the wind box.

A protecting ledge 48 mounted to the inner wall of the cupola slightly overhangs the holes 47 and prevents solid materials such as coke and metal from entering the holes 47 and lodging in the system. Although the hot gases in both forms of the invention have been shown to be bypassed in heat exchange relationship with the air and then brought back into the shaft of the cupola it is also possible to have the hot gases flow out into atmosphere through separate flues after the utilization of the heat thereof. However, it is more practical and economical to utilize the shaft of the cupola for carrying off the gases after the heat exchange has taken place.

By both of the arrangements shown an efficient heat exchange system is utilized for the pre-heating of the air supply for a cupola by the heat generated within the cupola in the usual operation of the same. It is to be noted that there is not only a uniform heating of the air blast but also that the air after being heated is subjected to uniform heat exchange conditions in passing to the tuyères, the heating arrangement being positioned in the same proximity to the tuyères at all points around the cupola.

Although we have described our invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. In a furnace having a wind box positioned around the body of the furnace for supplying blown air to a plurality of tuyères communicating with the furnace, said wind box having an inlet adapted to communicate with a source of blown air, partitions dividing the wind box into a portion adjacent the inlet, a portion adjacent the tuyères and an intermediate portion extended therebetween, a plurality of conduits extending through said intermediate portion to provide communication for the flow of air from the portion adjacent the inlet to the portion adjacent the tuyères, said intermediate portion having a hot gas chamber provided therein, said hot gas chamber substantially surrounding said conduits for heating the air flowing therein and substantially extending between the said portion of the wind box adjacent the inlet and the said portion

5 of the wind box adjacent the tuyères, said furnace having openings through the walls thereof to provide communication between the interior of the furnace and said hot gas chamber for the flow of hot gases generated by the furnace through said hot gas chamber, the air supplied to said tuyères being pre-heated by heat exchange with said hot gases.

2. In a furnace having a wind box positioned 10 around the body of the furnace for supplying blown air to a plurality of tuyères communicating with the furnace, said wind box having an inlet adapted to communicate with a source of blown air, a heater positioned in said wind box and extending around the annular extent thereof in uniform proximity to said tuyères, said heater dividing the wind box into a chamber immediately above, and a chamber immediately below, the said heater, said chamber above the heater communicating with the inlet and said chamber below the heater communicating with the tuyères, a plurality of conduits connecting said upper and lower chambers for passing air in the wind box through said heater from the upper 15 of said chambers to the lower of said chambers, said conduits being uniformly distributed around the wind box to equalize the flow therethrough, and connecting means connecting said heater with the interior of the furnace to by-pass hot gases from the furnace through said heater, the hot gases in said heater substantially surrounding said conduits to heat the air flowing therethrough to said tuyères.

3. In a furnace having a wind box positioned 20 around the body of the furnace for supplying blown air to a plurality of tuyères communicating with the furnace, said wind box having an inlet adapted to communicate with a source of blown air, a plurality of air conduits spaced at intervals around the body of the furnace and extending between a portion of the wind box adjacent the inlet forming an upper chamber and a portion of the wind box adjacent the tuyères forming a lower chamber for providing communication for the flow of air therebetween, a plurality of hot gas conduits disposed within, and spaced from the sides of, said air conduits, respectively, to heat the air passing through said air conduits, said hot gas conduits extending substantially the length of said air conduits from adjacent one of said chambers to adjacent the other of said chambers, and upper and lower connecting conduits extending through the wall of the furnace and connecting said hot gas conduits with the interior of the furnace for bypassing hot gases generated by the furnace through the said hot gas conduits.

4. In a furnace having a wind box positioned 25 around the body of the furnace for supplying blown air to a plurality of tuyères communicating with the furnace, said wind box having an inlet adapted to communicate with a source of blown air, a plurality of tubes for distributing equal portions of the blown air from the portion of the wind box adjacent the inlet forming an upper chamber to the portion of the wind box adjacent the tuyères forming a lower chamber, and a plurality of pipes extending within, and longitudinally of, said tubes substantially co-extensively therewith, said pipes being connected through the furnace body with the interior of the furnace to provide for the flow of hot gases generated by the furnace through said pipes, the air passing through said tubes from one chamber to the other chamber substantially surrounding

said pipes along substantially the length of the tubes and being heated thereby prior to entering said tuyères.

5. In a furnace having a wind box for supplying a blast of air to a plurality of tuyères, said wind box having an upper chamber encircling said furnace and a lower chamber encircling said furnace, said upper chamber having an inlet adapted to communicate with a source of an air blast and said lower chamber having outlets in communication with said tuyères and having a plurality of separate and uniformly spaced air conduits disposed around the circumferential extent of the furnace to provide communication between said upper and lower chambers, means for heating the air in said conduits comprising a plurality of holes extending through the wall of the furnace adjacent to, and below, said upper chamber and adjacent to, and above, said lower chamber, and intermediate chamber means providing communication between the upper and lower holes, said intermediate chamber means being positioned in heat exchange relationship with, and being extended along substantially the length of, said air conduits, the air passing through said air conduits being heated in its travel therethrough from the upper chamber to the lower chamber by the hot gases by-passed through said holes from the furnace and through the intermediate chamber means.

6. Apparatus for pre-heating air delivered to a furnace through a plurality of tuyères comprising, in combination, air chamber means and hot gas chamber means positioned around the exterior of the body of the furnace, said air chamber means comprising an upper chamber having an inlet adapted to communicate with a source of blown air, a lower chamber in communication with said plurality of tuyères, said upper and lower chambers encircling said fur-

nace, and a plurality of spaced conduits extending between said upper and lower chambers at uniform intervals around the furnace to provide communication between said upper and lower chambers, said hot gas chamber means being positioned intermediate of said upper and lower chambers of the air chamber means and being extended longitudinally of the furnace substantially the length of said spaced conduits, 10 said hot gas chamber means being in communication through the furnace wall with the interior of the furnace to permit hot gases from the furnace to flow therethrough, the air in said conduits being heated substantially throughout 15 its travel from the upper chamber to the lower chamber by said hot gas chamber means.

7. In a system for pre-heating air delivered through a plurality of tuyères to a furnace by the exchange of hot gases generated within the furnace, an upper compartment positioned around the body of the furnace and having an inlet in communication with a source of blown air, a lower compartment positioned around the body of the furnace and in communication with 20 said plurality of tuyères, a plurality of conduits substantially uniformly distributed around the body of the furnace and providing for the uniform flow of air therethrough from said upper compartment to said lower compartment, and 25 by-passing means in communication with the interior of the furnace for by-passing hot gases outside of the body of the furnace, said by-passing means extending substantially between said upper and lower compartments and along the extent of said conduits, the air being heated in 30 its travel through said conduits from the upper chamber to the lower chamber by the hot gases passing through said by-passing means.

HERBERT A. REECE.
OLIVER SMALLEY.
